DESIGN FOR A CAN KEY

Geno Lesti and Florence Wahl, Cleveland, Ohio

Application March 24, 1936, Serial No. 61,769

Term of patent 14 years

To all whom it may concern:

Be it known that we, Geno Lesti and Florence Wahl, each a citizen of the United States, residing at Cleveland, in the county of Cuyahoga and State of Ohio, have together invented a new, original, and ornamental Design for a Can Key, of which the following is a specification, reference being had to the accompanying drawing, forming a part thereof.

Fig. 1 of the drawing shows a plan view of a can key embodying our design; and

Fig. 2 is a section taken along the line 2—2 of Fig. 1.

We claim:

The ornamental design for a can key, substantially as shown.

GENO LESTI.
FLORENCE WAHL.
